UNITED STATES PATENT OFFICE.

BARTON E. KINGMAN, OF YONKERS, NEW YORK.

DISK-RECORD CABINET.

1,127,091.

Specification of Letters Patent.

Patented Feb. 2, 1915.

Application filed May 24, 1913, Serial No. 769,575. Renewed January 7, 1915. Serial No. 1,046.

To all whom it may concern:

Be it known that I, BARTON E. KINGMAN, a citizen of the United States, and a resident of Yonkers, in the county of Westchester, State of New York, have invented certain new and useful Improvements in Disk-Record Cabinets, of which the following is a specification, reference being had to the accompanying drawings, forming a part thereof.

My invention relates to filing cabinets and particularly to such as are adapted to contain disk records for phonographs.

One object of my invention is to provide a device of the character above indicated that shall be relatively simple and durable in construction and reliable and convenient in operation.

Another object is to provide in a device of this character an accessible selecting index and a single actuator whereby a record may be selected at will by setting the index and delivered to a retaining rack in response to the single actuator.

Other objects will be set forth hereinafter.

I will describe my invention in the following specification and point out the novel features thereof in appended claims.

Referring to the drawings, Figure 1 is a side elevation, in vertical section, of a cabinet constructed in accordance with and embodying the improvements of my invention. Fig. 2 is a front view of the same cabinet also in vertical section. A plan view of the cabinet is shown in Fig. 3. Fig. 4 is a detail view on a larger scale of the carriage which forms a part of the actuating mechanism of the device. Fig. 5 is a fragmentary plan view of one of the shelves which is adapted to receive the disk records showing some of the disk supports with intermediate spacers.

Like characters of reference designate corresponding parts in all the figures.

A cabinet 10 which has a base 11, supporting legs 12, back and side walls 13, 14 and 15, a top 16 and a door 17 in front, is provided with two compartments 18 and 19 of unequal size which are adapted to receive the disk records. Around the door is a casting comprising top and base strips 20 and 21, and side strips 22. The upper compartment is preferably of less height than the lower one but they are both substantially closed and fill the door opening so that they have the appearance of two shelves, one of

which is deeper and higher than the other. They are formed of a unitary structure comprising sides 23 and 24, a bottom board or shelf 25, a top 26, an intermediate shelf or partition 27, and back sections 28 and 29. The top 26 extends into grooves in the side walls 14 and 15 of the cabinet and the sides 23 and 24 are spaced from the side wall and are secured to the top 26 and the base 11 of the cabinet, the shelves 25 and 27 being secured to the sides 23 and 24. The back sections 28 and 29 extend downwardly from the top 26 and the shelf 27 respectively but leave openings 30 and 31 into the compartments at the lower portions thereof. There is a space not only above and below the compartments but also at the back, within the cabinet.

In order that phonograph record disks may be individually supported, a plurality of spacers 35 and 36 extend vertically from the bottom and top of each of the compartments. The spacers 35 of the lower compartment are comparatively wide and extend downwardly so as to support either a large or a small size disk as shown in Fig. 1. The front edge of each of the shelves 25 and 27 is beveled and provided with an index plate 37 which may be numbered or otherwise graduated to designate each record space, as shown in Fig. 5. The sides 23 and 24 of the compartment are notched at 40 and 41 to allow cushioned rods 42 and 43 which are mounted on levers 44 and 45 to swing into the cabinet sufficiently to permit the door to shut. These levers are pivoted to the sides 23 and 24 (see Fig. 2) and are arranged to support the rods in positions to which they are adjusted. A plurality of narrow tilting supports 50 and 51 are located in the record spaces and are pivoted on shafts or rods 52 and 53 which extend transversely of the cabinet near the bottom of the respective compartments. These supports extend backwardly through the openings 30 and 31 and rest on pads 54 and 55 and they are curved upwardly slightly at their front ends so that they tend to prevent the record disks, which rest upon them, from rolling out when the door is opened. The point of pivot for each support is however so placed as to permit it to tilt and cause its record to roll out as hereinafter pointed out. Depending from the inner end of each of the supports 50 is a rod 58 110

which is pivotally connected to it and extends loosely through a hole in a guide bracket 59.

The arrangement of parts is such that the lower ends of the rods 58, which are connected to the supports 50, lie in substantially the same straight line. The inner ends of the supports 51 extend close to the lower ends of the rods 58 and normally lie in the same horizontal plane so that they lie in two parallel rows. In order to dislodge one of the record disks, it is only necessary to produce an upward movement either on one of the rods 58 and the inner end of its connected support 50 or on the inner end of one of the supports 51 dependent upon the location of the record.

In order to select any one of a plurality of records which may be assumed to be located in the upper compartment, it is only necessary to produce a transverse movement of a carriage 61 by turning an adjusting hand wheel 60, until a lift pin 70 is directly under the rod 58 connected to the support 50 which is in the desired record space and to then actuate a push rod 63. If the desired record is in the lower compartment, the carriage is correspondingly adjusted until the lift pin is directly under the inner end of the support 51 which is in the desired record space, the push rod 63 being then actuated as before. The carriage is first moved forward by a lever 90 until the lift pin is under the inner ends of the supports 51 instead of under the rods 58.

The structural details embodied in the carriage and actuating mechanism illustrated are not essential to my invention and may be varied without departing from the spirit and scope of my invention.

The carriage illustrated comprises a block 65 (see Fig. 4) which is arranged to slide on a bridge comprising a pair of transverse guide rods 66 the ends of which are connected by cross pieces 67 and end brackets 67^a. These brackets are arranged to slide in guideways 68 which are mounted on the side walls of the cabinet near its lower back corners. The block 65 of the carriage has a projection 69 extending laterally from it and vertically perforated to receive a weighted selector or lift pin 70. The lift pin is in the form of a rod, extends through the perforated projection 69 and has an enlargement 71 which increases its weight and limits its downward movement. To each end of the carriage is secured a flexible cord 73 which extends over pulleys 74 near the respective ends of the guide rods and thence upward over the sprocket wheel or pulley 75 on a sleeve 76 which is rotatably mounted on a spindle projecting from the back 28 of the compartment 18. If a sprocket wheel as shown in Fig. 2 is employed, a section 67 of the flexible cord 73 is preferably com-

posed of a sprocket chain. Substantially parallel with the sleeve 76 is a hollow shaft 77 which at its inner end is geared to the sleeve 76 and on the outer end of which is the adjusting hand wheel 60. A bevel gear 78 is secured to this shaft, intermediate its ends and meshes with a bevel gear 79 which is affixed to and may form a part of an index plate 80. A series of numerals are inscribed on the upper surface of the plate 80 near its periphery and are visible one at a time as the disk is rotated, through a narrow slot 81 in the top 16 of the cabinet. By turning the hand wheel 60 the hollow shaft 77, the sprocket wheel 75, and the disk 80 are all rotated. The disk is thus rotated and the adjustment is continued until a predetermined number appears through the slot 81 in which position it may be held by a non-positive lock 62. At the same time 85 the rotation of the sprocket wheel adjusts the carriage 61 until the lift pin 70 is directly under rod 58 connected to the support 50 which is in a record space corresponding to the number visible through the slot 81. The push rod 63 extends through the hollow shaft 77 and is connected at its inner end to a lever 82, which is affixed to a shaft 83 intermediate its ends. This shaft extends transversely of the cabinet and a 95 pair of levers 84 are secured to it near its ends. A pair of levers 85 are pivotally secured at opposite points 86 on the side walls of the cabinet and are connected to the levers 84 by links 87. A transverse actuating bar 88 extends between the levers 85 and is directly under the lift pin 70 irrespective of the position to which it is adjusted. Consequently if the push rod 63 is actuated the levers 85 and the cross bar 88 100 will be raised and will actuate the lift pin 70. This action will be transmitted to the rod 58 which is directly above and in response to this action the support 50 will be tilted thereby allowing the disk record 110 which rests upon it to run out by gravity.

A bell crank lever 90 is pivotally mounted on the top 16 of the cabinet and is adapted to occupy two positions designated "upper" and "lower" (see Fig. 3). One arm 115 of the lever has a handle 91 while the other arm is adapted to cover a portion of the slot 81 and has on it a letter "A" which registers with slot 81 when the lever occupies its "upper" position and a letter "B" which 120 registers with the slot when the lever is in its "lower" position. The bell crank lever is connected by a lever, a link and a lever 93 to a transverse shaft 95 which has a pair of levers 96 secured to it near its ends. 125 From these levers depend a pair of links 97 which are connected at their lower ends with bell crank levers 98 pivoted at opposite points 99 on the side walls of the cabinet and connected by links 100 to the re- 130

spective shoes 67^a of the bridge. The size and arrangement of the links and levers is such that when the bell crank lever 90 is turned from its "upper" to its "lower" positions, the bridge and the carriage are so moved as to adjust the lift pin 70 from a position directly under the rods 58 to a position directly under the inner ends of the supports 51. The bar 88 is sufficiently wide so that the lift pin is always over it and is always lifted by it when the push rod 63 is actuated.

Assuming that a record B35 is desired; the door of the cabinet is opened, the guard rail 43 lowered, the bell crank lever 90 turned to its "lower" position, to show its letter "B" through the slot, the hand wheel 60 is adjusted until the number 35 appears through the slot 81 and finally the push rod 63 actuated. The adjustment of the bell crank lever 90 moves the carriage so that the lift pin is under the inner ends of the fingers 51, the adjustment of the hand wheel moves the carriage until the carriage is under the support in the desired record space and the movement of the push rod tilts the support and allows the record to run out. The cushioned rod 43 is preferably adjusted to some such position as shown in dotted lines in Fig. 1 and prevents the disk from falling out of the cabinet but at the same time permits it to roll out a sufficient distance so that it may be readily removed.

If record number A49 is desired, the bell crank lever 90 is turned to its "upper" position and the hand wheel is adjusted until the numeral 49 appears through the slot as shown in Fig. 3. The carriage is thus returned to the position in which it is shown in the drawings and is adjusted until the lift pin is directly under the rod 58 connected to the support 50 on which the desired record is mounted. The push rod when actuated tilts the finger and rolls the record to the position in which it is shown in broken lines in Fig. 1, the door 17 having first been opened and the cushioned rod 42 adjusted as indicated. Instead of members such as 50 and 51 being used as actual supports for the records, it is well within the scope of my invention to allow the records to rest on the shelves and to utilize these tilting members to be raised up behind the records to cause them to roll out. The cabinet may of course be arranged with the phonograph as a part of it or the record cabinet may be entirely independent of the phonograph.

What I claim is:

1. A filing cabinet comprising a compartment subdivided for records, a plurality of means for dislodging the records from the sub-divisions of said compartment, an actuator at a fixed point on the cabinet for said means, and an interposed adjustable selec-

tor between the actuator and one of said means.

2. A filing cabinet comprising a compartment subdivided for disk records, a plurality of tilting members for dislodging the records, a single actuator for said members, and an interposed adjustable selector lift pin between the actuator and one of said members.

3. A filing cabinet comprising a compartment subdivided for disk records, a plurality of tilting members for dislodging the records, a single actuator for said members, an interposed adjustable selector lift pin between the actuator and one of said members, and manually controlled means for adjusting the position of the lift pin.

4. A filing cabinet comprising a compartment subdivided for records, a plurality of tilting members for dislodging the records, a single actuator for said members, an interposed adjustable selector lift pin between the actuator and one of said members, an index, and means for producing a simultaneous adjustment of the index and of the position of the lift pin.

5. A filing cabinet comprising a compartment subdivided into a plurality of spaces for disk records, a plurality of tilting members in the bottom of the spaces for dislodging the records, a single actuator for said members, an interposed adjustable selector lift pin between the actuator and one of said members, an index having a plurality of marks for identifying the several spaces and operatively connected with the lift pin, and relatively stationary control means for simultaneously adjusting the index and the position of the lift pin.

6. A filing cabinet comprising a plurality of compartments, each subdivided into a plurality of record spaces, a plurality of means for dislodging the records, a single actuator for all of said means, an interposed selector between the actuator and one of said means, and means for adjusting the selector to select a desired compartment and a desired record space therein.

7. A filing cabinet comprising a plurality of superposed compartments, each subdivided into a plurality of spaces for disk records, a plurality of tilting members for dislodging the disk records, a single actuator for all of said members, an interposed selector between the actuator and one of said members, and means for adjusting the position of the selector to select a desired compartment and a member associated with a desired disk record space therein.

8. A filing cabinet comprising a plurality of compartments, each subdivided into a plurality of spaces for disk records, a plurality of means for dislodging the records, a single actuator for all of said means, an interposed adjustable selector between the ac-

- tuator and one of said means, manually controlled means for adjusting the position of the selector along one path to select one of said compartments, and independent means 5 for adjusting the position of the selector along a path at an angle to the first for selecting a single dislodging means in the compartment selected.

9. A filing cabinet comprising a plurality 10 of compartments subdivided into a plurality of spaces for disk records, a plurality of tilting members for dislodging the several records, a single actuator for all of said members, a manual push rod connected with 15 the actuator, a selector between the actuator and one of the members, means for adjusting the position of the selector to select one of the compartments, and means for adjusting the position of the selector in a 20 direction at an angle to the aforesaid adjustment for selecting one of the tilting members of the compartment selected.

10. A filing cabinet comprising a plurality 25 of compartments subdivided into a plurality of spaces for disk records, a plurality of tilting members for dislodging the several records, a single actuator for all of said members, a manual push rod connected with the actuator, a selector between the actuator 30 and one of said members, a lever operatively connected to the selector for adjusting its position backward and forward to select a single compartment, and a hand wheel adapted to be rotated for adjusting the position 35 of the selector from right to left to select one of the tilting members of the compartment selected.

11. A filing cabinet comprising an upper compartment and a lower compartment, 40 each subdivided into a plurality of spaces to receive disk records, a plurality of tilting members in the subdivisions of each compartment for dislodging the records, rods depending from the tilting members of the 45 upper compartment and extending close to the tilting members of the lower compartment, said members and rods being uniformly arranged whereby the inner ends of the members of the lower compartment of the 50 lower ends of the rods depending from the members of the upper compartment lie in two parallel rows, a bridge extending in a direction parallel with said rows and adjustable transversely thereof, a carriage on 55 the bridge adjustable in parallelism with said rows, a selector carried by said carriage, an actuator arranged to act upon the selector, and manually controlled means for 60 independently adjusting the bridge and the carriage and for producing a motion of the actuator.

12. A filing cabinet comprising an upper compartment and a lower compartment, each subdivided into a plurality of spaces 65 for receiving disk records, a plurality of 70 tilting members in the subdivisions of each compartment for dislodging the records, rods depending from the members of the upper compartment and extending close to the members of the lower compartment, said members and rods being uniformly arranged whereby the inner ends of the members of the lower compartment and the lower ends of the rods depending from the members of the upper compartment lie in two parallel rows, a bridge extending in a direction parallel with said rows and adjustable transversely thereof, a carriage on 75 the bridge adjustable in parallelism with said rows, a selector carried by said carriage, an actuator arranged to act upon the selector, a lever operatively connected to the bridge for adjusting the position of the selector in one direction, a hand wheel for adjusting the position of the selector in another direction, and a push rod for producing a motion of the actuator. 80

13. A filing cabinet comprising an upper compartment and a lower compartment each subdivided into a plurality of spaces for receiving disk records, a plurality of tilting members in the subdivisions of each compartment for dislodging the records, rods depending from the members of the upper compartment and extending close to the members of the lower compartment, said members and rods being uniformly arranged whereby the inner ends of the members of the lower compartment and the lower ends of the rods depending from the members of the upper compartment lie in two parallel rows, a bridge extending in a direction parallel with said rows and adjustable transversely thereof, a carriage on 90 the bridge adjustable in parallelism with said rows, a selector carried by said carriage, spaced pulleys on the bridge near its ends, a bar extending transversely of the cabinet under the bridge and arranged to act upon the selector, a lever operatively connected to the bridge near its ends for adjusting the position of the selector backward and forward, a hollow shaft, a sprocket wheel operatively connected thereto, a flexible cord embodying a sprocket chain cooperating with the sprocket wheel and connected over the pulleys to the carriage, a hand wheel for rotating the hollow shaft, and a push rod extending through the hollow shaft and operatively connected to the bar for raising 95 and lowering the bar and actuating the selector. 100

14. A filing cabinet comprising an upper compartment and a lower compartment each subdivided into a plurality of spaces for receiving disk records, a plurality of tilting members in the subdivisions of each compartment for dislodging the records, rods depending from the members of the upper compartment and extending close to the members of the lower compartment, said members and rods being uniformly arranged whereby the inner ends of the members of the lower compartment and the lower ends of the rods depending from the members of the upper compartment lie in two parallel rows, a bridge extending in a direction parallel with said rows and adjustable transversely thereof, a carriage on 110 the bridge adjustable in parallelism with said rows, a selector carried by said carriage, spaced pulleys on the bridge near its ends, a bar extending transversely of the cabinet under the bridge and arranged to act upon the selector, a lever operatively connected to the bridge near its ends for adjusting the position of the selector backward and forward, a hollow shaft, a sprocket wheel operatively connected thereto, a flexible cord embodying a sprocket chain cooperating with the sprocket wheel and connected over the pulleys to the carriage, a hand wheel for rotating the hollow shaft, and a push rod extending through the hollow shaft and operatively connected to the bar for raising 115 and lowering the bar and actuating the selector. 120

15. A filing cabinet comprising an upper compartment and a lower compartment each subdivided into a plurality of spaces for receiving disk records, a plurality of tilting members in the subdivisions of each compartment for dislodging the records, rods depending from the members of the upper compartment and extending close to the members of the lower compartment, said members and rods being uniformly arranged whereby the inner ends of the members of the lower compartment and the lower ends of the rods depending from the members of the upper compartment lie in two parallel rows, a bridge extending in a direction parallel with said rows and adjustable transversely thereof, a carriage on 125 the bridge adjustable in parallelism with said rows, a selector carried by said carriage, spaced pulleys on the bridge near its ends, a bar extending transversely of the cabinet under the bridge and arranged to act upon the selector, a lever operatively connected to the bridge near its ends for adjusting the position of the selector backward and forward, a hollow shaft, a sprocket wheel operatively connected thereto, a flexible cord embodying a sprocket chain cooperating with the sprocket wheel and connected over the pulleys to the carriage, a hand wheel for rotating the hollow shaft, and a push rod extending through the hollow shaft and operatively connected to the bar for raising 130 and lowering the bar and actuating the selector. 130

- members of the lower compartment, said members and rods being uniformly arranged whereby the inner ends of the members of the lower compartment and the lower ends 5 of the rods depending from the members of the upper compartment lie in two parallel rows, a bridge extending in a direction parallel with said rows and adjustable transversely thereof, a carriage on the bridge adjustable 10 in parallelism with said rows, a selector carried by said carriage, spaced pulleys on the bridge near its ends, a bar extending transversely of the cabinet under the bridge and arranged to act upon the selector, a lever operatively connected to the bridge near its ends for adjusting the position of the selector backward and forward, a hollow shaft, a sprocket wheel operatively connected thereto, a flexible cord 15 embodying a sprocket chain coöperating with the sprocket wheel and connected over the pulleys to the carriage, a hand wheel for rotating the hollow shaft, a push rod extending through the hollow shaft and operatively 20 connected to the bar for raising and lowering the bar and actuating the selector, and a cushioned guard rack adjustably supported in front of each compartment. 25
13. A filing cabinet comprising a compartment, vertically disposed parallel stationary spacers therein subdividing said compartment into a plurality of spaces for receiving disk records, tilting supports between said spacers, a transverse rod running through said supports forward of the 30
- center of gravity of the records thereon whereby the weight of said records hold said supports in a position with their upper surfaces downwardly inclined toward the rear of the compartment, manual means for moving a desired support to thereby raise the record thereon and to cause the supporting surface thereof to be inclined downwardly toward the front of the compartment to allow the record thereon to roll out of said compartment, and a transverse rod pivotally supported to be positioned in front of the records to hold them in the compartment or away from the records to arrest their movement as they roll out of the compartment. 35
16. A filing cabinet comprising a plurality of compartments, each subdivided into a plurality of record spaces, a plurality of means for dislodging the records, a single actuator for all of said means, an interposed selector between the actuator and one of said means, means for adjusting the selector to select a desired compartment, an indicator connected therewith, other means for adjusting the selector to a desired record space, 40 an index connected with said other means, and manual means for actuating the selector to discharge a desired record. 45
- In witness whereof, I have hereunto set my hand this 18th day of April 1913.
- BARTON E. KINGMAN.
